CLAIM

We claim the ornamental design for a sensor ball for dryer, as shown and described.

DESCRIPTION

FIG. 1 is a front perspective view of a sensor ball for dryer showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof; and,

FIG. 8 is another front perspective view thereof.
